BY *W. O. U. - B. L.*

ATTORNEYS.

UNITED STATES PATENT OFFICE.

FREDERICK TRAUTWEIN, OF FREEPORT, NEW YORK, ASSIGNOR TO TRAUTWEIN CORPORATION, OF BROOKLYN, NEW YORK, A CORPORATION OF NEW YORK.

DESIGN FOR A TIRE-TREAD.

57,065.

Specification for Design.

Patented Feb. 1, 1921.

Application filed November 23, 1920. Serial No. 426,093. Term of patent 14 years.

To all whom it may concern:

Be it known that I, FREDERICK TRAUTWEIN, a citizen of the United States of America, residing at Freeport, in the county of Nassau and State of New York, have invented a new, original, and ornamental Design for a Tire-Tread, of which the following is a specification, reference being had to the drawing forming a part thereof.

Figure 1 is a detail plan view showing the tread.

Fig. 2 is a perspective view showing a section of the tire with the tread therein.

I claim:

The design for a tire tread, substantially as shown.

FREDERICK TRAUTWEIN.
